CONTROL SYSTEM

Edward M. Sorensen, Dayton, Ohio

Original application May 16, 1940, Serial No.
335,517. Divided and this application January
8, 1941, Serial No. 373,619

6 Claims. (Cl. 179—171)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to control systems, and particularly to those systems in which the controlled device at the remote station is of a highly sensitive character; for example, the relays which control the movements of an airplane and therefore respond to any deleterious condition found anywhere within the control circuit. Among such conditions, in case the controlling circuit employs tube amplifiers, is the variation of the filament supply potential which normally causes corresponding variations in the plate current. The present invention, therefore, more particularly relates to an improved system by which compensation is introduced to offset changes in electron emission brought about by variations in the filament supply potential.

This is a division of my copending application Ser. No. 335,517, filed May 16, 1940, for Radio remote control system.

The primary object of the invention is to provide an emission compensator for tube circuits which find particular application in remotely controlled systems, and which give continuously variable operation of the control device and will be capable of energizing or utilizing any amount of power at the control device, regardless of the energy applied to the control. In systems of the character mentioned, for example in the control of an airplane which contains electro-responsive devices extremely sensitive to the received signals and variations thereof, it is necessary that all causes by which deleterious electrical effects are introduced into the system be eliminated. One of the main defects resides in the manner of the occasional changes in the filament emission of one or more of the tubes employed in the circuit, particularly the first tube of the system, and such changes, unless otherwise compensated, are bound to give rise to undesirable effects in the delicately responsive signal devices at the control station, even to the extent of producing false indications.

In the system shown in the drawing there is illustrated a single-stage amplifier which might form part of an intricately controlled system requiring a sensitive response to a controlling circuit, or apparatus which may be remotely or locally positioned and may involve a wire or radio link circuit. The circuit is particularly useful in any amplifier where a great amount of stability is necessary for variations in supply po-

tentials. It is a known fact that when the filament temperature of an electronic tube is increased, a greater number of electrons is emitted from the filament, and vice versa a reduction in the filament temperature produces a decrease in the electron emission. This is true in connection with both vacuum and gas tube types, and also in those tubes which employ indirectly heated cathodes, because the temperature of the heater filament in that case bears a direct relation to the temperature of the cathode. The emission compensator disclosed in this application depends for its operation on the use of the Edison effect, and the potential changes set up from a diode plate to its cathode will vary with the temperature of the cathode. The manner in which this potential varies is controlled by the rate at which the cathode heats up or cools off, depending upon the supply potential to the cathode.

The circuit comprises a diode tube 1 having its plate 2 connected to the grid return 3 of the grid 4 contained in an amplifying tube 5. A resistor 6 is inserted in this circuit, and the upper end of the resistor may be connected to the output circuit of a preceding tube or an antenna, indicated at 7. The grid return is also connected by a resistor 8, through a battery 9, to the cathode 10 of the diode tube. The battery and cathode are commonly connected to ground, or as shown to the —B supply terminal indicated at 11.

With this circuit the bias on the grid 4 will vary by measuring the bias from the grid 4 to the cathode 12 of the triode tube 5 in a direct relation with the filament potential as supplied to the filamentary heater 14, assuming that the heater is supplied from the same potential which supplies the filament 15 of the diode tube. The manner in which this bias potential varies follows very closely the value of the voltage needed to bias the grid to maintain the plate current of the anode 16 at the same value which was flowing prior to a change in filament potential.

The battery 9 is poled as indicated, i. e. its negative terminal is connected to the cathode 10 of the diode tube 1. Under these circumstances it will be noted that the diode plate 2 will have a positive potential with reference to the cathode 10. Any changes in current being drawn by said diode tube will be represented by the voltage drop which takes place across the resistor 6. Thus it can be readily shown that for any value of emission which takes place across

the diode tube a corresponding voltage will be set up between point 3 and point 17.

In some cases it has been found necessary to include some of the filament supply potential voltage as a bias voltage on the grid, especially in cases where the emission of the tube varies a great deal for a small filament potential change. By placing a potentiometer 18 in the return circuit of the cathode 12 a portion of any voltage variation across the filament circuit will also be represented on the grid. The potentiometer should be adjusted to provide the desired amount of bias voltage. Fixed resistances may be added to each side of the potentiometer, if necessary. This added bias voltage, together with the voltage as set up across the diode tube 4, provides the necessary control to hold the plate current of the triode at a steady value for large changes in filament potential. These changes in filament potential may be as great as 100 per cent. That is to say, for a tube which has a normal operating voltage of 6.3 volts, the filament supply voltage may vary from 4 to 8 volts with the emission remaining constant over this range. It may also be pointed out that this additional voltage may be obtained from the plate supply voltage in those cases where the plate supply voltage is obtained from the same source as the filament supply voltage, as any variation in the filament voltage will cause a variation in the plate supply voltage in the same proportion.

It is apparent that in any tube system in which the disclosed compensating circuit is employed this circuit serves to render the current response of the tubes independent of filament voltage variation within the range compensated, and responsive only to the signal applied to the grids of those tubes from an external source. This is very important when the filament voltage cannot be maintained constant, as would probably be the case in the power supply of aircraft. In the event of a change in filament potential variation without provision for emission compensation in response to such change, any relays which may be connected to the output circuit of the tube 5 for controlling a motor circuit of the aircraft would be affected by changes in the plate current which would not be caused by a change in the grid signal, and would therefore result in erratic operation of the motor.

While I have made particular mention of the use of my novel emission compensating circuit in connection with the control of airplanes and circuits therefor, it will be understood that the compensator has universal uses in all places where the filament supply voltage tends to change or fluctuate and constant sensitiveness and stability of operation are necessary.

It will be understood that I desire to comprehend within my invention such modifications as come within the scope of the claims and the invention.

Having thus fully described my invention, what I claim as new and desire to secure by Letters Patent, is:

1. An electronic circuit for compensating for variation in emission of the cathode emitter of an electronic valve due to filament potential variation, said circuit comprising a diode electronic tube having its anode in series with the grid return of said electronic valve and its filament potential supplied from the same source as the filament of the electronic valve, a circuit including a battery and a resistance connecting the grid return of said electronic valve to the cathode of

said diode tube, said battery being arranged with its negative pole toward said cathode and said resistance being intermediate said battery and said grid return, the values of said battery, resistance and said diode tube being such that the potential between said grid return point and the junction of said battery and cathode is equally divided across said diode tube and said battery circuit.

2. In an amplifying system which includes a tube of the indirectly heated type, a plate, a control grid, a cathode, a filamentary heater for said cathode contained in said tube, a source of energy for energizing said filamentary heater, and means for preventing variations in the potential of said source of energy from affecting the plate current, said means comprising a rectifier connected between the cathode and the control grid, said rectifier having a filamentary cathode which is energized from the same source as the filamentary heater of said tube.

3. In an amplifying system, a tube containing a cathode, control grid and plate, said cathode being activated from a source of energy, and means for preventing potential variations of said source from deleteriously affecting the plate current, said means comprising a rectifier having an anode, an indirectly heated cathode and a filamentary heater for the last-mentioned cathode, said anode being connected to the control grid of the amplifier and said filamentary heater being connected to said source of energy, and said indirectly heated cathode being connected to the cathode of said amplifier.

4. In an amplifying system, a tube containing a cathode, control grid and plate, said cathode being activated from a source of energy, and means for preventing potential variations of said source from deleteriously affecting the plate current, said means comprising a rectifier having an anode, an indirectly heated cathode, a filamentary heater for the last-mentioned cathode, said anode being connected to the control grid of the amplifier, said filamentary heater being connected to said source of energy, said indirectly heated cathode being connected to the cathode of said amplifier, and a biasing potential connected between the plate of the rectifier and its cathode.

5. In an amplifying circuit, a tube including an anode, control grid, indirectly heated cathode and a filamentary heater therefor, said heater being connected to a source of current, and means for preventing variations of potential of said source from deleteriously affecting the plate current, said means comprising a resistor connected across the legs of the filamentary heater and an adjustable tap taken from the resistor to the indirectly heated cathode, said means also including a rectifier connected between the indirectly heated cathode and the control grid, said rectifier having a filamentary member which is connected to said source of current and subject to the same potential variations which affect the amplifier tube, and an anode in said rectifier tube connected through a resistor to the control grid of the amplifier tube and biased positive with respect to the filament of the rectifier tube.

6. In an amplifying circuit, a tube including an anode, control grid, indirectly heated cathode and a filamentary heater therefor, said heater being connected to a source of current, and means for preventing variations of potential of said source from deleteriously affecting the plate current, said means comprising a resistor connected across the legs of the filamentary heater

and an adjustable tap taken from the resistor to the indirectly heated cathode, said means also including a rectifier connected between the indirectly heated cathode and the control grid, said rectifier having an anode, an indirectly heated cathode and a filamentary heater, the filamentary heater of said rectifier being connected to said source of current and therefore being responsive to the same variations of potential as the fila-

mentary heater of the amplifier tube, the indirectly heated cathode of said rectifier tube being connected directly to the filamentary heater of the amplifier tube, the anode of said rectifier tube being biased positive with respect to the cathode of the rectifier tube and connected to the control grid of the amplifier tube.

EDWARD M. SORENSEN.
